(57) **CLAIM**

The ornamental design for a pair of footwear soles with color contrasting lateral portions, as shown and described.

DESCRIPTION

FIG. 1 is an anterior (front) view of the footwear sole with color contrasting lateral portion;

FIG. 2 is a posterior (rear) view of the footwear sole with color contrasting lateral portion of FIG. 1;

FIG. 3 is a lateral view of the footwear sole with color contrasting lateral portion of FIG. 1;

FIG. 4 is a medial view of the footwear sole with color contrasting lateral portion of FIG. 1;

FIG. 5 is a top view of the footwear sole with color contrasting lateral portion of FIG. 1;

FIG. 6 is a bottom view of the footwear sole with color contrasting lateral portion of FIG. 1; and,

FIG. 7 is a perspective view of the footwear sole with color contrasting lateral portion of FIG. 1.

The footwear sole with color contrasting lateral portion shown in FIGS. 1-7 is for a left foot. The footwear sole with color contrasting lateral portion for a right foot is a mirror image of the footwear sole with color contrasting lateral portion of the left foot.

The dash dot dash broken lines depict the claim boundary and form no part of the claimed design. The surface inside the dash dot dash boundary forms no part of the claimed design.

The shading indicates a portion of the sole which has a contrasting color relative to the remainder of the claimed design.
